UNITED STATES PATENT OFFICE.

WILLIAM SEILER, OF KOKOMO, INDIANA, ASSIGNOR OF ONE-THIRD TO CHARLES HAMMOND, OF KOKOMO, INDIANA.

AUTOMOBILE LOCK.

1,410,609.

Specification of Letters Patent. Patented Mar. 28, 1922.

Application filed August 23, 1919. Serial No. 319,521.

To all whom it may concern:

Be it known that I, WILLIAM SEILER, a citizen of the the United States, residing at Kokomo, in the county of Howard and State of Indiana, have invented certain new and useful Improvements in Automobile Locks, of which the following is a specification.

This invention relates to automobile locks and the prime feature of the invention is the provision of a locking mechanism which will cut off the supply of fuel from the motor and render it impossible to operate the motor of the vehicle until the locking mechanism is again operated to again turn on the supply of fuel, thereby guarding against the possibility of the automobile being stolen.

A further feature of the invention is the provision, in connection with the means for cutting off the flow of fuel, of a lock, preferably of the combination type, for controlling the operation of the fuel controlling mechanism.

A further feature of the invention is the provision of means for automatically operating the fuel cut off, whereby the fuel will be automatically cut off when the pressure of the lock mechanism is released therefrom, by manipulating the combination feature of the lock or when the lock is broken, in an attempt to turn on the fuel.

A further feature of the invention is the manner in which the fuel cut off mechanism is applied to use, either by building the cut off directly into the carbureter so as to intercept the flow of the fuel before it enters the mixing chamber of the carbureter, or attaching the cut off exteriorly of the carbureter in such manner as to intercept the flow of fuel to the carbureter.

Other objects and advantages will be hereinafter more fully set forth and pointed out in the following description and specification.

In the accompanying drawings which are made a part of this application:

Figure 1 is a side elevation of a carbureter, showing a cut off mechanism built into the same.

Fig. 2 is a sectional view thereof as seen 50 on line 2—2 Fig. 1.

Fig. 3 is a view similar to Fig. 2, showing the cut off mechanism outside of the carbureter and attached thereto.

Fig. 4 is an edge elevation of a dial to be 55 used in connection with the locking mechanism.

Fig. 5 is a top plan view of the dial.

Referring to the drawings in which similar reference numerals designate corresponding parts throughout the several views, 1 indicates a carbureter which may be of any preferred type, said carbureter having a fuel intake port 2, a mixing chamber 3 and a feed port 4, as is usual in carbureters.

In order to entirely cut off the supply of fuel from the mixing chamber of the carbureter and thereby prevent the operation of the motor to which the carbureter is attached, a cut off valve 5 is so positioned as to intercept the fuel on its passage from the usual supply tank to the mixing chamber of the carbureter, and as shown in Fig. 2, the valve 5 is built into the carbureter and is seated in a socket 6, formed in a wall 7, of the carbureter above the mixing chamber 3, the lower end of the socket 6 communicating with the mixing chamber 3 through a port 8.

The valve 5 is preferably in the form of a ball and is held in the socket 6 by threading a cap 9 into a recess 10 in the wall 7, the cap having an opening therethrough through which part of the valve may project, the wall of the opening through the cap having a circumferential shoulder 11, against which the valve strikes and which limits the outward movement of the valve.

The fuel intake 2 discharges the fuel above 90 the cap 9 so that the fuel in its passage to the mixing chamber, must pass through the socket 6 and port 8 to enter the mixing chamber, consequently, when the ball valve 5 is seated against the shoulder 11, the flow 95 of fuel to the mixing chamber is entirely stopped, and the engine can not be started or operated until the valve is again opened.

The valve 5 is automatically closed by means of a spring 12, which is positioned in the socket 6 below the valve, the tension of the spring 12 being such as to constantly direct outward pressure on the valve.

The lower end of the intake 2 discharges the fuel into the lower end of a chamber 13 and to prevent the fuel from passing upwardly in the chamber 13, a diaphragm 14 10 is positioned above the cap 9 and is held spaced therefrom by a shoulder or ledge 15, the space between the cap and diaphragm providing a passage for the fuel from the intake 2 to the socket 6. When the engine 15 is to be operated, the diaphragm 14 is depressed, which lowers the ball valve 5 away from its seat 11 and permits the fuel to flow into the mixing chamber of the carburetor.

Any suitable means may be employed for 20 depressing the diaphragm for opening the valve, but preferably a combination lock mechanism is employed so as to render it practically impossible for any one not familiar with the combination of the lock 25 mechanism to open the valve 5 and reestablish the feed of the fuel to the carburetor. In carrying out this feature of the invention, a plurality of tumblers 16 are entered into a casing 17 and said casing then 30 entered into the chamber 18 and so secured therein that it will be impossible to gain access to the tumblers without first removing them from the chamber.

One of the tumblers 16 is provided with 35 a plunger 18, which engages the upper face of the diaphragm 14, and by arranging the tumbler so that when turned to a certain position, the tumbler having the plunger thereon, will move inwardly, the diaphragm 40 will be depressed and held in its depressed position until the lock mechanism is again operated to release the pressure on the diaphragm, when the valve will be automatically closed by the pressure of the 45 spring 12, and held in such closed position until pressure is again applied thereon.

By arranging the valve in this manner, it will remain closed, even though the tumblers were removed in an effort to release the valve from its seat, and even then the machine could not be driven, as it would be necessary to hold the valve depressed.

In order to conveniently operate the 55 tumblers, a rod 19 is extended from the tumblers to any convenient point on the machine, preferably the dash, where it will be convenient for the operator to manipulate the dial 20 attached to the upper end of the 60 rod, said dial being of the ordinary type, although, preferably, the graduations are designated by letters instead of numerals, in which the combination may consist of certain letters of a name, and thus be more 65 readily remembered.

It is to be understood, of course, that any suitable locking mechanism may be used in connection with the cut off valve, so long as the lock is arranged to direct pressure on the diaphragm for releasing the valve 70 when the motor is to be operated, and to remove the pressure therefrom, when the supply of fuel is to be cut off.

When the valve mechanism is attached exteriorly of the carburetor, as shown in Fig. 75 3 of the drawings, a housing 21, is provided for the casing 17, this housing having the fuel intake formed therein, and likewise the valve is located in this housing. When this form of device is used, the housing 21 is provided with an extension 22 which threads into the ordinary form of opening 23 in the carburetor, the port 8 being extended through the extension and communicating with the usual fuel intake 24, 85 of the carburetor.

The operation of this form of locking and valve mechanism is the same as that described in the first instance, the only difference being in the location of the valve 90 mechanism.

From the foregoing it will be seen that it will be practically impossible for any one, other than the owner or driver of the car to start the engine of the machine, unless 95 others know the combination of the locking mechanism, so as to manipulate the locking mechanism to direct pressure on the diaphragm and release the valve from its seat, or if it is a key operated locking mechanism, is provided with a key, as the removal or tearing away of the locking mechanism will not effect the release of the valve, as there would then be no means of applying 100 the pressure on the valve.

The possibility of the car being stolen or driven away by any one not entitled to the use of the car, is very remote, and gives to the owner or driver of the car a feeling of safety that he would not otherwise 110 have, if the locking mechanism was not installed on the car.

The invention claimed is:

1. In a valve structure a valve seat, a ball valve projecting part way through said seat, means for automatically moving said valve against said seat for closing passage through said seat, a diaphragm anchored adjacent said valve and free therefrom and on the opposite side of the valve from the 120 valve seating means, and a lock means for depressing said diaphragm for removing and retaining said valve away from its seat.

2. In a valve structure a valve seat, a ball valve at one side of said seat and a diaphragm on the opposite side of said valve seat from said valve and unattached to the valve adapted to be moved against said valve for disengaging and holding the same 130

from its seat and a lock mechanism for operating said diaphragm.

3. In a valve structure a valve seat, a ball valve at one side of said valve seat a part 5 of which extends through the seat, means for automatically seating said valve, a diaphragm on the opposite side of said valve seat from the valve independent of and

adapted to be moved against said valve, and a combination lock mechanism for moving 10 said diaphragm against said valve for moving the valve away from its seat.

In testimony whereof I hereunto affix my signature.

WILLIAM SEILER.
